UNITED STATES PATENT OFFICE.

GERHARD C. KLIWER, OF CHICAGO, ILLINOIS, ASSIGNOR OF ONE-HALF
TO JOHN H. PALMER, OF CHICAGO, ILLINOIS.

TABLET-MAKING MACHINE.

No. 839,156.

Specification of Letters Patent.

Patented Dec. 25, 1906.

Application filed May 6, 1904. Renewed October 31, 1906. Serial No. 341,448.

To all whom it may concern:

Be it known that I, GERHARD C. KLIWER, a citizen of the United States, and a resident of Chicago, in the county of Cook and State of Illinois, have invented certain new and useful Improvements in Tablet-Making Machines, of which the following, when taken in connection with the drawings accompanying and forming a part hereof, is a full and complete description, sufficient to enable those skilled in the art to which it pertains to understand, make, and use the same.

The object of this invention is to obtain a machine by means of which a large number of tablets for medicinal or food purposes may be made within a given time by a single attendant.

A further object of the invention is to obtain a machine for the purpose named which is compact in shape, strong and durable, and not liable to get out of order.

In the drawings referred to as accompanying and forming a part of this specification, Figure 1 is a front elevation of a machine embodying this invention with a portion of the jackets thereof broken away to expose to view the operative parts covered thereby. Fig. 2 is a top plan view of the machine with the hopper thereof, which is illustrated in Fig. 1, taken from the machine to expose the operative parts of the machine to view. Fig. 3 is a side elevation of an elevating-roller and the bearing thereof forming an element in the machine embodying this invention. Fig. 4 is a front elevation of the elevating-roller and bearing illustrated in Fig. 3. Fig. 5 is a vertical sectional view of the main drum of the machine embodying this invention with plungers shown in elevation on the right-hand side of the figure. Fig. 6 is a top plan view of a movable abutment forming an element of this invention. Fig. 7 is a side elevation of the abutment illustrated in Fig. 6. Fig. 8 is a front elevation of a spring-abutment used in combination with the abutment illustrated in Figs. 6 and 7 to form the bearing of a compression-roller forming a part of the machine embodying this invention, and Fig. 9 is a side elevation of the spring illustrated in Fig. 8.

A reference-letter applied to designate a given part is used to indicate such part throughout the several figures of the drawings wherever the same appears.

A is the base of the machine, and *a a* are the legs of such base.

B B are standards rigidly secured at the respective lower ends thereof to the base A and at their upper ends respectively secured to the spider C.

D is a ball-bearing step mounted on base A to support the shaft E of the drum F. The drum F is provided with the hub G (see Fig. 5) and the spokes *g g g g*, extending from the hub to the annular part *g'* of the drum. I prefer to cast the drum F, hub G, spokes *g*, and the annular part *g'* of cast metal and in one piece, as in such case when the several dies, plungers, and punches hereinafter described are mounted thereon there is but little liability for change in the relative position of the several parts.

H, H', I, I', and J are annular flanges on drum F, and may consist of ring secured to the periphery of such drum. I prefer to have the several flanges H, H', I, I', and J of steel or wrought-iron, and hence where the drum F is made of cast metal the rings forming such flanges are carefully fitted to the periphery of the drum and there secured in place.

h h are annular jackets covering the flanges H H' and I I' and the springs R R' on the several plungers.

K K and L L are plungers longitudinally movable in the annular flanges H H' and I I', respectively.

M M are thimbles removably secured in annular flange J. Thimbles M M are preferably made of hardened steel and provided with holes therethrough (indicated by broken lines *m m* in Fig. 5) to form dies.

The plungers K K are provided at the lower ends thereof, respectively, with the punches *k k*, which are closely fitted to the holes in annular flange J corresponding thereto, (indicated by the broken lines *m m* in Fig. 5 of the drawings.) The plungers L L are respectively provided with punches *l l*, which are also closely fitted to the holes indicated by the broken lines *m m* in thimbles M M. When thus constructed, the punches *k* and *l* and the thimbles M M, provided with holes corresponding to the punches, may be removed from the machine, and punches of a different diameter may be inserted in place of the ones removed, and thimbles provided with holes therethrough of substantially the same size as the punches used may be insert-

ed in the annular flange J. Provision is thus made for adjusting the machine to compress medicinal or food tablets of different diameters.

5 When the plungers K K are respectively in a raised position, the lower ends of the punches secured therein are raised out of the holes in the thimbles M M, corresponding thereto, and when such plungers K K are in a 70 depressed position the punches k k secured therein are well entered into the holes in thimbles M M corresponding thereto, respectively. When the plungers L L are in a depressed position, the punches l l, secured 75 therein, are entered in the holes in the thimbles M M, respectively, corresponding thereto to form abutments against which the material contained in such holes and underneath the punches k k are pressed to compress such 80 material into tablets, and when such punches l l are in a raised position the upper ends of such punches are substantially in the same plane as the upper end of the thimbles M M, so that the tablets formed in the machine 85 are raised thereby out of the holes in which they have been compressed and will be swept from the annular flange J by any obstruction placed in the path thereof by the rotation of the annular flange J, with drum F, to which it is secured, as, say, by plate V. (See Fig. 1.)

To provide for the longitudinal movement of the plungers K K, I mount the depressing-rollers N N N N rotatably on the inner ends 90 of screws P P and secure such screw to respective standards B B, as hereinafter described.

O O are springs through which the screws P P, respectively, extend, and Q Q are abutments through which such screws also extend. The upper end of the springs O O abut 95 against the under side of the spider C, (see Fig. 1) so that as the screws P P are turned in the screw-threaded holes q q in abutment 100 Q the depressing-rollers N N N N are moved slightly up or down and incidentally sidewise. The exact distance to which the several plungers K K are forced down as said plungers are carried underneath the depressing-rollers N 105 N N N in the rotation of the drum F is thereby controlled.

On each one of the plungers K K there is mounted a coiled spring R, (see Fig. 1,) with the lower end thereof abutting against the 110 annular flange H' and the upper end thereof abutting against the collar S (which is rigidly secured in place) on the plunger. After a plunger is forced down by the depressing-roller N thereover in the rotation of the drum F such plunger is raised to its initial position 115 as it comes out from under the roller N by the resiliency of such spring R. The several plungers L are respectively provided with a 120 spring R', one end whereof abuts against the annular flange I' and the other end against

the collar S', which is firmly secured in place on the plunger. After a plunger K has been carried underneath a depressing-roller N, and thereby depressed, the plunger L corresponding thereto is then carried over the one of the 70 elevating-rollers T T, and thereby raised, as illustrated in Fig. 1 of the drawings, and as such plunger is raised the spring R' thereon is thereby compressed, and hence by the resiliency of such spring the plunger is returned 75 to its initial position after the same has passed over the roller T.

t t are standards on which the shaft t' t' of rollers T T are respectively mounted. Standard t is secured to the base A. 80

To supply material to be compressed into tablets by this machine, I provide a hopper (as hopper U, Fig. 1) with as many down-spouts as are desired thereto. I have illustrated a machine provided with four down-spouts u u u u, four depressing-rollers N N N N, and four elevating-rollers T T T T, with a 85 large number of plungers, punches, and dies on the drum F.

The down-spouts U are expanded at the 90 lower end u' thereof, where such down-spouts are joined to the plate V, Fig. 1, so that the contents of the down-spouts may be spread along the top of the annular flange J. The plate V may also serve to brush from the top 95 of the annular flange J tablets made in the machine, as hereinbefore stated.

In the operation of this machine the drum F is made to continuously revolve, as by bevelled gear-wheels W W' and shaft X. As the drum rotates the several plungers are brought underneath the depressing-rollers N N and over the elevating-rollers T, respectively, so that where four of each kind of rollers are placed in the machine, as illustrated in the drawings, and twenty-six sets of the several plungers, punches, and dies are placed in such machine, as is illustrated in the drawings, one hundred and four tablets are made at each revolution of the drum F 110 and shaft E.

I claim—

1. In a machine for making tablets, a rotatable vertical shaft, a drum on the shaft, dies and an upper and lower series of punches on the drum, yieldingly-mounted wheels arranged to depress the punches of the upper series a plurality of times at each revolution of the drum, means to adjust the tension of the several wheels to obtain corresponding density to all of the tablets made in a given die at each revolution of the drum, and means to lift the punches of the lower series a number of times corresponding to the number of depressions of the punches of the upper series 120 at each revolution of the drum; substantially as described.

2. The combination of a base, standards on the base, a rotatably-mounted vertical shaft, a drum on the shaft punches and dies on the 130

drum and rotatable wheels yieldingly mounted in the path of the upper series of punches, the mechanisms yieldingly holding the wheels comprising bolts on which the wheels rotate, leaf-springs through which the bolts extend, and means to move the bolts longitudinally to vary the tension of the springs, respectively; substantially as described.

3. A base, standards on the base, a flat spring provided with a hole therethrough, a movable abutment fitting against one of the

standards and provided with a screw-threaded hole therethrough, a screw extending through the hole in the spring, through the screw-threaded hole in the movable abutment and through one of the standards, and a wheel rotatably mounted on the inner end of the screw; substantially as described.

GERHARD C. KLIWER.

In presence of—

CHARLES TURNER BROWN,
CORA A. ADAMS.
